UNITED STATES PATENT OFFICE.

ANDREW F. EPPES, OF STONY CREEK, VIRGINIA.

IMPROVEMENT IN PLOWS.

Specification forming part of Letters Patent No. **102,789**, dated May 10, 1870.

To all whom it may concern:

Be it known that I, ANDREW F. EPPES, of Stony Creek, in the county of Sussex and State of Virginia, have invented a new and Improved Plow; and I do hereby declare that the following is a full, clear, and exact description of the construction and operation of the same, reference being had to the accompanying drawings, making a part of this specification, in which—

Figure 1 is a front elevation with the two-winged share in place, the others being removed; and Fig. 2 is a side elevation with the one-winged share, and Fig. 3 is an elevation of the share *d*.

This invention consists of sundry improvements in the construction of plows, whereby they are rendered more useful in operation.

In the drawings, *A* is the plow-stock, attached at its top to one side of the plow-beam, and provided with an offset, *a*, which brings it directly beneath the plow-beam, so that a brace, *a'*, may be extended straight back from the stock to the plow-handles. The lower part of the stock has a horizontal cutter, *b*, projecting from both sides and adjustable in different

sockets of the stock, so that it may shave off grass-roots whether the plow run deep or shallow. For making drills a front and shallow share, *c*, projects forward from the stock, and is provided with a vertical colter, *c'*, to cut the sod. I use, one at a time, three shares, *d*, for simply turning a furrow, *e*, provided with one wing, *e'*, for throwing dirt to one side, and *h*, provided with two wings, *h' h'*, for throwing direct to both sides. The shares are used in conjunction with the drill-point *c*, and are attached by bolts and nuts to the stock *A* just below the offset.

Having thus described my invention, what I claim as new, and desire to secure by Letters Patent, is—

The stock *A*, made with an offset, *a*, and brace *a'*, all in one piece, in combination with the root-cutter *b* or *d*, drill-point *c* and cutter *c'*, and adjustable hinged share *i* or *h'*, in the manner and for the purpose described.

A. F. EPPES.
